UNITED STATES PATENT OFFICE.

EDWARD TERRY, OF BRIXTON, ENGLAND.

JET-NOZZLE FOR CARBURETERS.

1,147,763.

Specification of Letters Patent. Patented July 27, 1915.

Application filed May 16, 1913. Serial No. 767,957.

To all whom it may concern:

Be it known that I, EDWARD TERRY, a subject of the King of Great Britain, residing at Brixton, in the county of Surrey, England, have invented new and useful Improvements in Jet-Nozzles for Carbureters, of which the following is a specification.

This invention has reference to carbureters for internal combustion engines.

10 It has for its object to provide an improved jet nozzle for carbureters whereby a more efficient explosive mixture may be obtained with a considerable saving of combustible while at the same time obviating the accumulation of soot on the valves and

15 sparking plugs.

In its broadest aspect the invention contemplates a jet nozzle for the carbureters of internal combustion engines in which the 20 liquid combustible is caused to impinge upon a gauze so mounted directly in the path of the jet that a predetermined amount of combustible only shall be volatilized in passing through said gauze at each induction stroke of the engine.

More specifically considered the invention 25 comprises a jet nozzle for the carbureters of internal combustion engines having a gauze supported directly in the path of the 30 jet of liquid combustible means whereby the relative position of said gauze with respect to the orifice of the jet nozzle may be varied in accordance with requirements and means whereby any unvolatilized combustible may 35 be led to a tank or receptacle.

In order that my invention may be readily understood and carried into effect by those skilled in the art to which it appertains I 40 will now proceed to describe the same fully for which purpose reference is to be had to the accompanying drawings in which:

Figure 1 represents a vertical section of a 45 jet nozzle for internal combustion engines embodying this invention. Fig. 2 is a top plan view thereof.

In the embodiment of the invention illustrated the jet nozzle *a* threaded as at *b* to adapt it for connection to a carbureter (not shown) is provided with a cup or receptacle *c* having an orifice *d* formed in the base thereof for a purpose which will be presently explained. Secured to said cup *c* are two vertical rods *e* serving to support an adjustable thimble *f* in the center of which 55 is an orifice *g* covered with fine mesh wire

gauze *h*. In the drawing the thimble *f* is shown as being provided with holes *i* through which the rods *e* pass, appropriate set screws *j* being provided for securing the thimble in the desired position.

60 The operation of my improved carbureter jet nozzle is as follows: Upon each induction stroke of the piston a quantity of liquid combustible is sucked through the nozzle *a* from the float chamber or other receptacle 65 for the supply of the fuel and projected through the restricted orifice *k* directly onto the gauze *h*. A portion only however of the liquid fuel passes through the gauze *h* and orifice *g* in the thimble *f* when it is 70 immediately volatilized and mixing with the air supplied to the carbureter passes directly into the induction pipe and thence to the combustion chamber of the cylinder in a gaseous condition. That portion of the 75 combustible which is unvolatilized falls into the cup *c* flows through the orifice *d* in the base thereof to a suitable receptacle for re-use or I may provide a pump to return it 80 directly to the float chamber.

A carbureter jet-nozzle in accordance 85 with this invention possesses many advantages over devices of the kind as heretofore constructed for it will be apparent that by means of my improved device only sufficient liquid fuel is volatilized at each induction stroke as is required to form the correct explosive mixture the surplus being recovered for re-use instead of being sucked into the combustion chamber as is often the case 90 with carbureters as heretofore constructed thus preventing the formation and deposit of soot upon the valves and sparking plugs.

I claim:

1. A jet nozzle for carbureters comprising 95 the combination with an ejector supply pipe for the liquid combustible, a cup surrounding a portion of said pipe and having a discharge orifice therein, supports carried by said cup and a gauze supporting member adjustably secured to said supports.

2. A jet nozzle for carbureters comprising 105 the combination with an ejector supply pipe for the liquid combustible, a cup surrounding a portion of said pipe and having a discharge orifice therein, supports carried by said cup and an inverted thimble having a gauze covered aperture therein adjustably secured to said supports.

3. A jet nozzle for carbureters comprising 110

ing the combination with an ejector supply pipe for the liquid combustible, a cup surrounding a portion of said pipe and having a discharge orifice therein, supports carried by said cup and an inverted thimble having a gauze covered aperture therein adjustably mounted on said supports and

means for retaining said thimble in any desired position upon said supports.

EDWARD TERRY.
